[57] CLAIM

The ornamental design for ornamental child's pillow in the fanciful form of a bear in football uniform, as shown and described.

DESCRIPTION

FIG. 1 is a perspective view of the ornamental child's pillow in the fanciful form of a bear in football uniform taken from above the left leg corner;

FIG. 2 is a top plan view thereof;

FIG. 3 is a bottom plan view thereof;

FIG. 4 is a left side elevational view the right side being a mirror image thereof;

FIG. 5 is a front side elevational view thereof; and,

FIG. 6 is a back side elevational view thereof.

The stippled shading represents conventional fabric and is understood to extend uniformly throughout the areas represented.
